UNITED STATES PATENT OFFICE.

EDWARD C. WALKER, 3D, OF BROOKLINE, MASSACHUSETTS.

METHOD OF ELECTROLYTIC PRODUCTION OF PERCHLORIC ACID.

1,271,633.

Specification of Letters Patent.

Patented July 9, 1918.

Application filed April 23, 1917. Serial No. 163,766.

To all whom it may concern:

Be it known that I, EDWARD C. WALKER, 3d, a citizen of the United States, and resident of Brookline, in the county of Norfolk 5 and State of Massachusetts, have invented new and useful Improvements in Methods of Electrolytic Production of Perchloric Acid, of which the following is a specification.

It has been known for a long time that 10 perchlorates are formed by electrolysis of chlorides, and that perchloric acid (HClO_4 or ClO_3OH) can be produced in small amounts by oxidation of hydrochloric acid during electrolytic decomposition of solutions there- 15 of. Heretofore, however, so far as I am informed and have been able to ascertain, the quantity of perchloric acid obtainable by electrolysis, under known conditions, has been so small that no approximation to 20 practical commercial production has been attained. By my process herein described and claimed, perchloric acid is produced with economy consistent with commercial requirements.

25 Variable factors in electrolytic production of perchloric acid, which influence the rate, quantity, and economy of manufacture, are: (1) duration of electrolysis; (2) current-density; (3) concentration of the acid 30 electrolyte; (4) temperature; (5) anode material.

In respect to these variable factors, my process is characterized by the following conditions:

35 (1) The duration of electrolysis is influenced by the other four variable factors, (as illustrated by the table hereinbelow), but under given conditions the electrolysis is continued until practically all the hydro- 40 chloric acid has disappeared from the solu-

tion and until practically all the chloric acid has been electrolytically oxidized to perchloric acid. Upon concentrating this electrolyzed solution, pure perchloric acid is obtained, since the hydrochloric and chloric acids are evaporated off with the excess water. 45

(2) The current-density on the anode has a range from one-tenth to five-tenths ampere per square centimeter, preferably not 50 more than three-tenths for highest efficiency.

(3) The hydrochloric acid electrolyte has a range of concentration from one-tenth normal to one normal.

(4) The temperature may range from 55 about 0° C. to about 50° C.; but for efficient production of perchloric acid, temperatures at the lower end of this range should be maintained, especially during the later stages of the process, as will presently be 60 explained.

(5) As anode materials carbon or graphite, fused magnetite, or platinum are available. Carbon may be used for the intermediate oxidation of hydrochloric acid to 65 chloric acid but, by reason of the low over-voltage of oxygen on this material, platinum or fused magnetite is preferably to be used for the complete oxidation of chloric acid to perchloric acid. For a chemically pure final product, platinum is preferably to be used throughout, as anode material. 70

The effects of variations in duration of electrolysis, current density, and concentration of acid electrolyte are illustrated by the 75 following table which shows my observations of an electrolysis with an anode of platinum, and temperature maintained at 20° C.

80

Duration of electrolysis 4 ampere-hours.

Current density.....	0.102	0.137	0.171	0.204
HCl at start.....	.0984	.0984	.0984	.0984
HCl present at end of 4 ampere-hours.....	.0123	.0138	.0152	.0157
Per cent. HCl present.....	12.5	14.0	19.9	22.7
Per cent. HCl lost.....	44.0	41.2	59.0	57.0
Per cent. HCl converted to HClO_4	3.10	1.50	5.38	2.15
Per cent. HCl converted to HClO_4	41.6	43.0	15.0	17.9
Eq.* HClO_4 per liter.....	.0031	.0015	.0329	.0066
Eq.* HClO_4 per liter.....	.0410	.0423	.0370	.0443
Watt hours per gram HClO_4	42.0	47.4	39.8	40.5
		97.2	51.0	58.5

* Equivalent to.

	Duration of electrolysis 7 ampere-hours.		
Current density	0.137	.510	0.204
HCl at start	.251	.510	.251
HCl present at end of 7 ampere-hours	.0110	.0550	.020
Per cent. HCl present	4.38	10.8	7.97
Per cent. HCl lost	65.4	74.9	63.0
Per cent. HCl converted to HClO_3	.500	4.12	
Per cent. HCl converted to HClO_4	29.4	10.2	30.1
Eq.* HClO_3 per liter	.0012	.0210	
Eq.* HClO_4 per liter	.0736	.0520	.0755
Watt hours per gram HClO_4	37.8	43.1	45.3

* Equivalent to.

[It should be noted that in obtaining the above data, 150 ccm. of acid was electrolyzed under the conditions specified, and then analyzed. Thus the process was not strictly continuous, and the tabulated results are all relatively lower than those for the continuous process herein described.]

My investigations justify the conclusion, that reasonably, or commercially economical production of perchloric acid is conditioned upon dilution of the hydrochloric acid electrolyte, with one normal, as the practical maximum limit, current density with five-tenths ampere per square centimeter as the practical maximum limit, temperature with 50° C. as the practical maximum limit. The 5 minimum limit of temperature is fixed at the freezing point of the electrolyte and is practically 0° C., since water is the best available agent for cooling the electrolytic cell.

Since the formation of the intermediate product—chloric acid—takes place with the greatest efficiency of temperatures ranging from 25° C. to 50° C., in solutions of hydrochloric acid whose concentrations lie within the higher specified range, and with the 10 lower current densities; and whereas the lower temperatures and higher current densities are more favorable to the subsequent oxidation of chloric acid to per-chloric acid, the process may with appreciable technical 15 advantage be characterized by maintenance of the higher temperatures, lower current densities, and higher concentrations of hydrochloric acid during the early stages, and subsequent depression of temperature, and 20 increase in current density. As the transition of product from HClO_3 to HClO_4 is gradual rather than abrupt, the stage when the temperature will advantageously be 25 lowered will be ascertained by examination 30 of samples of solution, taken from time to time, and obviously will vary with variations of the factors involved. For practical and commercial purposes, however, the electrolysis should be continuous, and may 35 be carried out so as to take advantage of the above stated facts by using an apparatus as is illustrated in the drawings annexed, in which—

Figure 1 is a diagrammatic representation 40 of the apparatus;

Fig. 2 is a side elevation of one of the electrolysis cells;

Fig. 3 is a top plan view of the cell; and

Fig. 4 is an end elevation of the cell.

50 Referring to Fig. 1: A is the tank holding the supply of dilute HCl used as the elec-

trolyte. B is the first electrolyzing unit which is maintained at the proper temperature in the higher range, and in which (1) is the platinum, magnetite, or carbon anode 55 of such dimensions as to give the proper current density. The tank itself (2) is constructed of copper with a silver lining, and serves as the cathode. The cooling may be effected by spraying the cooling water (by 60 means not shown) on the outside of the tank B. The flare (9) at the top of the tank is desirable to resist the corrosion at the junction of liquid and air due to the evolved chlorin gas, and gives this protection because of the presence of a stream of hydrogen gas which is always between it and the active chlorin.

(4) is a siphon overflow which maintains the level of the liquid "B" at the correct 70 point. It is constructed of silver where it emerges from the tank, and a glass joint is made at the point G, the rest of the siphon being of glass. This construction is necessary as no metal except platinum will withstand the chlorin gas dissolved in the solution passing through the apparatus unless protected by evolution of cathodic hydrogen.

The unit "C" is similar to unit "B", and is maintained within the lower temperature 80 range, so as to produce HClO_4 at highest efficiency from the HClO_3 which exists in high concentration in the solution entering "C".

(3) is an anode either of platinum or 85 fused magnetic iron oxid, of such size as to give the proper high current density.

(6) is another siphon overflow similar to (4) and empties into the tank "D".

From tank "D" the electrolyzed solution 90 passes through a valve (7) into a fused silica cascade evaporator "E" and "F".

The solution flowing into receptacle R is nearly pure perchloric acid of concentration up to 60%.

95 In Figs. 2, 3 and 4, the cell 2, with flaring top 9, is shown. The preferred construction and dimensions are; that the cell should be of seamless copper, lined with silver, eighteen inches long, one inch wide, and five 100 inches high to the flare 9; width at the top of the flare three inches.

An apparatus comprising units "B" and "C" of the dimensions shown in the detail drawing will produce approximately three (3) pounds of 60% perchloric acid in twenty-four hours' operation.

What I claim and desire to secure by Letters Patent is:

1. The process of producing perchloric acid, which consists in subjecting to electrolytic action a hydrochloric acid solution, strength one normal, or less, with current-density at five-tenths ampere, or less, per square centimeter.
2. The process of producing perchloric acid, which consists in subjecting to electrolytic action a hydrochloric acid solution, strength one normal, or less, with current-density at five-tenths ampere, or less, per square centimeter, at a temperature not materially exceeding 50° centigrade.
3. The process of producing perchloric acid, which consists in subjecting to electrolytic action a hydrochloric acid solution, strength one normal, or less, with current-density at five-tenths ampere, or less, per square centimeter, at a temperature not materially exceeding 50° centigrade at the initial stages of the process, and reducing the temperature as the process progresses.

4. The process of producing perchloric acid, which consists in subjecting to successive stages of electrolytic action a hydrochloric acid solution, strength one normal or less, with current-density at five-tenths ampere or less per square centimeter, at a temperature not materially exceeding 50° centigrade, in the initial stage, and at materially reduced temperature in a subsequent stage, maintaining flow of electrolyte through the initial stage, to and through the subsequent stage.

5. The process of producing perchloric acid, which consists in subjecting to successive stages of electrolytic action a hydrochloric acid solution, strength one normal or less, with current-density at five-tenths ampere or less per square centimeter, at a temperature not materially exceeding 50° centigrade, in the initial stage, and at materially reduced temperature in a subsequent stage, maintaining flow of electrolyte through the initial stage, to and through the subsequent stage, drawing off and concentrating the perchloric acid solution thus produced.

Signed by me at Boston, Massachusetts, this 14th day of April, 1917.

EDWARD C. WALKER, III.
